UNITED STATES PATENT OFFICE.

ERNEST F. WEGE, OF LA CROSSE, WISCONSIN, ASSIGNOR TO STERLING MACHINERY COMPANY.

CONCRETE-MIXER.

1,091,264.

Specification of Letters Patent. Patented Mar. 24, 1914.

Application filed October 10, 1912. Serial No. 725,008.

To all whom it may concern:

Be it known that I, ERNEST F. WEGE, a citizen of the United States, residing at La Crosse, in the county of La Crosse and State 5 of Wisconsin, have invented certain new and useful Improvements in Concrete-Mixers; and I do declare the following to be a full, clear, and exact description of the invention, such as will enable others skilled in the art 10 to which it appertains to make and use the same.

This invention relates to mixers, and more especially to those adapted particularly for the mixing of concrete and the like; and 15 the object of the same is to produce a machine of this character wherein a polygonal mixing receptacle is mounted fixedly within parallel rings standing at right angles to its axis, one ring being supported radially by 20 bearing rollers and the other axially by thrust rollers and a bearing pin and driven by connection with a source of power in such manner that it cannot well become accidentally displaced. This object is accomplished by constructing the machine as hereinafter more specifically described and 25 claimed, and as shown in the drawings wherein—

Figure 1 is a side elevation of the machine 30 complete, with the doors of the motor housing open. Fig. 2 is a rear elevation, and Fig. 3 a cross section on the line 3—3 of Fig. 1. Fig. 4 is a plan view of the machine, omitting the hood to show the lower rollers. Fig. 35 5 is a vertical cross section on the line 5—5 of Fig. 1, and Fig. 6 is a cross section through the mixing receptacle.

This machine is preferably mounted on a bed or body B which is supported by wheels 40 W so that it may be drawn from point to point. The motive power is shown as a gasoline engine E mounted within a housing H which has doors D.

In the embodiment illustrated in the accompanying drawings, the engine shaft is connected by a belt 1 with a power shaft 2, and this shaft is capable of being connected by a clutch, broadly indicated by the numeral 3, with a driving shaft 4 mounted in 45 bearings in a suitable framework 5 carried on the body B, and itself having a power gear 6. The clutch may be moved to opened or closed position by means of a lever 7.

Coming now to the details of the present 50 invention, the mixing receptacle is prefer-

ably formed of sheet iron or steel in the form of a cube 10 having one end 11 open and elevated so that the material to be mixed may be fed thereinto, and the axial line 12 passing through the center of this open end 60 stands oblique to a horizontal and transverse to the body B. To maintain the receptacle in this position it is surrounded at its upper and lower ends respectively by two rings 13 and 14, the lower ring 14 having teeth 15 on 65 its upper face meshing with the power gear 6 whereby the receptacle is rotated. These rings I would dispose near the upper and lower ends respectively of the receptacle, and connect them firmly with the corners 70 thereof by means of brackets 16 or otherwise, and the rings should be formed of rolled or pressed steel and with the proper cross section so that they serve as tracks for supporting the receptacle: That is to say, the upper 75 ring 13 has its radially outer edge resting on a pair of rollers 17 journaled within a bracket 18 carried on the bed B and covered by a hood 19 to protect it from dust and dirt; while the lower face of the lower ring 80 14 rests on the flat peripheries of two rather larger rollers 20 which are journaled near the extremities of a cross bar 21 extending across the lower end of the receptacle and held in angularly positioned standards 22 85 rising from the bed B. It will be observed from Fig. 3 that one of these rollers is directly opposite the power gear 6 which engages the teeth 15, and the position of the roller 20 at that point prevents disengagement 90 in case any of the teeth become worn. Said thrust rollers sustain most of the weight of the receptacle and its contents, while the smaller or bearing rollers hold its open and lighter end elevated somewhat 95 higher than its closed and heavier end. In addition to these four points of support for the receptacle 10, I preferably employ a journal at the center of its lower end, consisting of a stub shaft 25 projecting along 100 the axial line 12 of the receptacle and mounted in an eye or bearing 26 at the center of the cross bar 21. Thus it will be seen that the receptacle is very firmly supported at five points—upon four rollers and on its 105 axial bearing in addition—and yet it can be instantly removed when it is desired to replace it by another receptacle for any reason. As shown the gear 6 is located on a line with the opposite roller 20 carried at one 110

end of the beam with the gear ring 14 disposed between them, whereby the ring 13 located at the opposite end of the receptacle will always ride smoothly upon its rollers 5 and the same will not have a tendency to jump from the roller during the rotation of the receptacle. Thus it will be seen that a very strong, durable and practical machine is constructed for the purpose and one that 10 will remain operative under all conditions. In removing it the gear 6 is first slipped off its shaft and the latter run back in its bearings, then the upper ring is lifted off the smaller rollers 17 and out from under the hood 19, and finally the entire receptacle is 15 moved upward along its axial line 12 so that the lower ring 14 is raised out of contact with the larger rollers 20 and the stub shaft 25 is drawn longitudinally out of the bearing 20 or socket 26. If another receptacle is to be inserted in place of the one removed it will be put in place by a movement the reverse of that just described. It is quite possible to provide one of these machines with several 25 different receptacles mounted within rings which are all of a uniform size and disposition, and any receptacle having such rings can replace the one illustrated and described.

One corner of the closed lower end of the 30 receptacle is provided with an outlet opening, covered by a hinged door 30, the hinge 31 being rather nearer the center of one of the flat sides and the latch 32 (if one be provided) being rather nearer the corner 35 of the receptacle 10. Along the upper and lower edges of the door I would have cleats 33 and 34, the latter possibly formed by beading the edges of the metal from which the sides of the receptacle are made, the 40 purpose of these cleats being to prevent the door from being pushed outward by the weight of the material within the receptacle as it is tumbled about during the rotation thereof. This door obviously opens inward, 45 and for the purpose of opening it I provide a rod 35 extending loosely through an eye or guide 36 at one side of the open end 11 of the receptacle, and having a hand hold 37 by which it may be manipulated. Drawing 50 upon this hand hold swings the door inward, and this can only be done when the receptacle has rotated until the door is above the pin 25 where the weight of the contents does not fall against and hold the door 55 closed; thereafter when the receptacle has turned for a half revolution, the door-opening comes at the bottom, and the contents are delivered over a chute 38 carried by the bed B, and into a suitable receptacle placed 60 beneath the chute or onto the roadway if it be so desired. For agitating the material within the receptacle while the latter is rotating, I provide oblique baffles 39 of strap

metal secured to the interior of its side walls as best seen in Figs. 5 and 6, and by preference one of these stands in position to be struck by the door when it is opened and thus to prevent the door from being opened too wide, and hence serves the double purpose of a baffle and a door-stop. 65 70

The operation of this device will be obvious to one skilled in the art. When the engine is started and the clutch thrown in, the power gear 6 meshing with the teeth 15 in the ring 14 causes the receptacle to 75 rotate on its several points of support, and as it does so the material is thrown into the open upper end 11 thereof and tumbled about by the baffles 39. After the concrete or other material has been agitated and 80 mixed for a sufficiently long time, the operator draws on the hand hold 37 so that the rod 35 causes the door to swing open as seen in Fig. 6, which must be done at a time when the door stands above the stub 85 shaft 25 so that the weight of the contents of the receptacle shall not hold the door closed. Thereafter, on the next half revolution of the receptacle, some of the contents fall out the opening over the chute 90 38, and this continues until all the contents of the receptacle have been discharged. Thereafter the door is again closed, the receptacle charged by delivering the proper materials into its open upper end 11, and 95 the operation repeated.

What is claimed as new is:

The combination of a supporting structure, a bracket disposed obliquely on one side of said structure and having a series 100 of longitudinally alined adjacently mounted rollers, angularly positioned standards on the other side of said structure, a bar supported by said standards and having rollers at opposite ends, and a bearing mid-way 105 thereof, a mixing drum open at one end and having a centrally disposed stub shaft at its other end designed to engage the bearing in said bar, flat annular members encircling said drum adjacent its opposite ends and 110 secured thereto, the upper member being positioned to peripherally engage the bracket carried rollers on one side of said supporting structure and the lower member having its flat outer face engaged with the rollers 115 at the other side of the structure, one of said annular members having teeth, and a power driven pinion meshing with said teeth.

In testimony whereof I have hereunto set 120 my hand in presence of two subscribing witnesses.

ERNEST F. WEGE.
